JOHN MILLAR, OF PATERSON, NEW JERSEY.

Design No. 4,461, dated November 8, 1870.

DESIGN FOR RUSTIC FENCE.

The Schedule referred to in these Letters Patent and making part of the same.

To all whom it may concern:

Be it known that I, JOHN MILLAR, of Paterson, in the county of Passaic and State of New Jersey, have invented a new and improved Design for Rustic Fence; and I do hereby declare that the following is a full, clear, and exact description thereof, which will enable others skilled in the art to make and use the same.

The nature of my design is fully represented in the

accompanying photographic illustration, to which reference is made.

I claim as my invention—

The design for a rustic fence, as shown.

The above specification of my invention signed by me this 18th day of August, 1870.
